VINCENT G. APPLE, OF DAYTON, OHIO

MOLD FOR INSULATING AN ARMATURE

Application filed February 3, 1930. Serial No. 425,685.

This invention relates to molds for insulating armatures and particularly for armatures comprising a core, a winding, and a commutator, the winding being composed of magnet wire which is preferably covered with a layer of fibrous or other absorptive material.

The object of the invention is to provide a mold comprising means to hold the core and the commutator in suitably spaced apart relation, and the winding to a definite shape, while fluid insulation is forced in, through and about the turns of the winding and over the joints between the winding and the commutator, where it may be hardened while the mold is still in place, to the end that all of the fluid insulation used will be retained and be held in proper shape while it is being hardened, that the several parts may be permanently held in proper relation thereby, and that the covering thus formed will prevent the absorption of oil, moisture or other foreign matter by the winding and protect it against physical injury.

I attain this object by the structure hereinafter described, reference being had to the drawing wherein—

Fig. 1 is an enlarged top plan view of the mold on a reduced scale.

Fig. 2 is an axial cross section taken at 2—2 of Fig. 1.

Fig. 3 is a transverse section taken at 3—3 of Fig. 2.

Fig. 4 is a transverse section taken at 4—4 of Fig. 2.

Fig. 5 is a top plan view of a segmental supporting ring.

Fig. 6 is a detail view of one of the parts of the mold.

Similar numerals refer to similar parts throughout the several views.

The armature 10 comprises a sleeve 11 upon which is fitted the core 12 and the commutator 13. The winding is composed of a plurality of turns of cotton or similarly covered magnet wire the ends of which may be joined to the commutator segments in the usual or any manner desired. The winding heads 14 and 15 extend beyond the ends of the core as in common practice.

The commutator 13 is of somewhat unusual construction being composed of a number of segments 16 imbedded in the core 17 of insulation. An annular groove 18 encircles the outer surface dividing the risers 19 from the brush track 21. While the core 17 extends outwardly between the segments 16 to keep them spaced apart, it does not extend entirely to the brush track but only to the line 22, thus leaving spaces 23 extending lengthwise between adjacent segments as deep as the annular groove 18, forming what is generally termed an undercut commutator. The brush track 21 may be trued up when necessary by taking cuts across its diameter from the outer end and ending in the annular groove 18 without danger of cutting into the risers 19.

Since the commutator is of the undercut variety the mold for insulating the armature must necessarily provide means to keep the insulation from filling the grooves 23, and accordingly suitable metal spacers are made a part of the mold.

The base 26, in the main, is in the form of a rectangular plate but has an integral collar 27 extending upwardly from its upper surface. A smooth round opening 28 extends vertically through the collar and base and is enlarged at 29 and still further enlarged at 31. A stepped member 32 having three outside diameters corresponding to the base openings 28, 29 and 31 respectively is held in place by screws 37. Member 32 has central openings of three sizes 38, 39 and 41, the opening 38 being equal to the extreme outside diameter of the commutator 13, and the parts 39 and 41 being filled in by the stepped plug 42.

Member 32 is cut with a series of equally spaced radial slots 43 corresponding to the segments of the commutator in number and to the space between them in thickness. These slots extend from the top of the member 32 through its two upper diameters to the line 44. The sheet metal spacers 46 are then put in the slots, and occupy not only all of the space removed when cutting the slots but extend inwardly into the opening 38 to fill the empty space between the commutator seg-

ments. It will be seen that when the parts 26, 32, 42 and the spacers 46 are assembled as shown the spacers cannot move in any direction from their respective positions. When 5 these parts are so assembled and the screws 37 are put in place they are not again taken apart except for making repairs.

The plate 48 is rectangular in outline and has a central opening 49 counterbored as at 10 51. Opening 49 fits freely over the collar 27, and the main cylinder 52 has an annular rib 53 which fits freely in counterbore 51. Cylinder 52 has an opening 54 of uniform diameter all the way through. A ring 56 fits 15 freely in opening 54 and has a central opening shaped to suit the winding head 15 and an inwardly turned annular rib 57 which fits into the groove 18 of the commutator, and in order to be enabled to remove the collar 56 after the armature has been insulated it is 20 separable as at 58 into three parts. The core 12 rests on the upper edge of ring 56 and it is in this manner that the core and commutator are held positively spaced apart 25 while the process of insulating the armature is taking place.

The plunger 59 has a central opening 61 to fit freely over sleeve 11 and is hollowed out at its lower end to go over the winding head 30 14. The lower end of plunger 59 ultimately rests on the core 12 whereupon the upper end comes flush with the top of cylinder 52 as shown. The tapped opening 62 is placed so as to come over one of the winding slots of the 35 armature core. Opening 62 may be used as a vent to permit the escape of excess liquid when the plunger 59 is being pressed down into place, and it may be left open when baking the structure to permit the escape of 40 gases generated by the heat of baking.

In operation the plate 48 is laid over the collar 27 of base 26 with the length of the plates at right angles to each other (see Fig. 1). The armature 10 is then put upright with 45 the commutator 13 inserted in the opening 38, the spacers 46 extending into the spaces 23. The three part ring 56 is now put around head 15 and the main cylinder 52 is put over the ring with the rib 53 in the counterbore 51. A measured quantity of the fluid insulation 50 is now poured into the top of cylinder 52 and the plunger 59 is inserted and pressed downward in a suitable press to the position shown.

55 After the liquid insulation has been injected into the mold as described the liquid must be converted into a solid and the process necessary for so converting it depends on the nature of the liquid being used. Most of the 60 commercial insulating varnishes are susceptible of being converted into a solid by the application of heat, and where this kind of insulation is employed the entire structure comprising the mold and its contents may be 65 placed in a suitable oven and baked. Since

the mold is transferred from the press to an oven, suitable clamping means not shown for holding the mold parts together while baking is taking place must be provided.

When the insulation is sufficiently hard the 70 armature is removed from the mold. Since the rectangular base 26 and the rectangular plate 48 of the mold are assembled with their longest dimensions at right angles one to the other, each projects over the other (see Fig. 1) in 75 such a manner that the plate 48 may be readily held while the base 26 is pushed off of the mold pulling the spacers 46 of the mold from the spaces 23 of the commutator. The plate 48 may then be taken off easily since it is fitted freely to the rib 53 and does not make contact with any other member. The armature together with the plunger 59 and the ring 56 are now pushed endwise from the cylinder 52. The plunger 59 and the collar 56 may 80 now be removed, the collar radially one section at a time, whereupon the armature will be insulated.

Having described a mold embodying my 90 invention, I claim—

1. In a mold for insulating an armature, the combination of an oblong base having a collar extending upwardly from its upper surface, said collar having an internal diameter adapted to receive the commutator, an oblong plate having an opening fitting freely over said collar, said base and said plate being assembled with their longest dimensions the one at right angles to the other, a cylinder supported on said plate concentric with said collar, a ring fitted in the lower end of said cylinder having a central opening shaped to the front winding head and a plunger fitted in the upper end of said cylinder having a central opening shaped to the back winding head. 95

2. For insulating an armature comprising a core, a winding on said core, and a commutator axially spaced apart from said core, said commutator having an annular groove extending around its outer diameter between the active portion of the commutator and the risers, a mold comprising, in combination, a base portion to contain the active portion of the commutator, a main cylinder extending upwardly from said base portion, said main cylinder having an internal diameter equal to the outside diameter of said armature core, a ring slidably fitted to the lower end of said main cylinder, said ring having an axial length equal to the distance from the armature core to the active portion of the said commutator and an annulus at its lower end fitted to the annular groove in said commutator, said ring being composed of a 100 number of separate segments, and a plunger, having its lower end hollowed out to suit the back winding head of said armature, slidably fitted to the upper end of said main cylinder. 105

3. For insulating an armature comprising a core, a winding on said core, and a commutator axially spaced apart from said core, said commutator having open spaces between the segments at the active surface, a mold having a lower section to receive the active portion of said commutator, said lower section comprising in combination, sheet metal spacers equal in number, in spacing and in thickness to said open spaces in said commutator but wider and longer and having outwardly extending L ends at the bottom, a stepped member having a cylindrical upper portion of two outside diameters, the smaller outside diameter at the top, and two inside diameters, the larger inside diameter at the top, said larger inside diameter corresponding to the outside diameter of the commutator, said cylindrical upper portion having slots to receive said L shaped sheet metal spacers, said slots completely containing said L shaped spacers except where they extend radially inward into said inside upper diameter of said cylindrical upper portion, a base portion having two inside diameters to fit over the two said outside diameters of said cylindrical upper portion, and a plug to fit the smaller of the two said inside diameters.

30 In testimony whereof I affix my signature.
